ABSTRACT OF THE DISCLOSURE

A pressure storing chamber in the form of an expandable tubular member is mounted in sealed relation about a perforated section of an underground water pipe to meet demand during pressure fluctuations. A casing protectively enclosing the perforated pipe section limits the volume to which the chamber expands and cooperates to pressure seal the axial ends of the tubular member about the pipe.

This invention relates to pumping systems and more particularly to pumping systems associated with private deep well water sources.

A primary object of the present invention is to provide in combination with a deep well pumping system, pressure storing facilities for meeting the normal demands for water under pressure without the use of any pressure water tanks.

A further object of the present invention is to provide in combination with a water supply conduit to which a submersible water pump is connected, water pressure compensating facilities for meeting fluctuating demand by means of one or more expandable units connected between the discharge end of the pump and the water outlets.

An additional object of the present invention is to provide pressure regulating units adapted to be mounted below ground within a well bore in a vertical position or alternatively in a horizontal position and cooperating with pressure responsive control means to meet the requirements of the water supply system within an operating pressure range of discharge pressure without any water storing tanks.

In accordance with the foregoing object, the water supply conduit is provided with one or more expandable chamber units consisting of a perforated pipe section enclosed within an elongated, tubular member made of a yieldably elastic material such as rubber forming an expandable chamber about the perforated pipe section in fluid communication with the supply conduit through which water under pressure is supplied from the pump to the outlets being serviced. Thus, as long as water under pressure within the operating pressure range is being conducted through the supply conduit, the chamber enclosed within the tubular member is expanded radially to limits prescribed by an external rigid casing enclosing one or more of the expandable units, each unit also including facilities for limiting axial expansion of the tubular member.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a side elevational view of an installed pumping system with which the present invention is associated;

FIGURE 2 is an enlarged partial sectional view of the pumping equipment with one of the pressure compensating units shown in section;

FIGURE 3 is a sectional view through the pressure compensator unit in a different operative condition than that shown in FIGURE 2;

FIGURE 6 is a perspective view of one of the parts associated with the pressure compensator unit;

FIGURE 7 is a perspective view illustrating other parts associated with the pressure compensator unit;

FIGURE 8 illustrates an alternative arrangement for the equipment associated with the present invention;

FIGURE 9 is a simplified circuit diagram showing the control system associated with the present invention.

Referring now to the drawings in detail, FIGURE 1 illustrates a typical, deep well pumping system generally denoted by reference numeral 10 wherein a supply of water is obtained by means of a commercially available, submersible water pump unit located at the bottom of a well bore 12 to which a drop pipe 14 is connected. The drop pipe 14 is in fluid communication with a water supply pipe 16 connected to a plurality of outlets such as the water outlet 18. Energization of the pump unit is controlled through a motor control box 20 and a pressure switch device 22. Accordingly, the water supply conduit 16 is connected to the outlet pipe 24 by means of a T-coupling 26 to which the pressure switch device 22 is connected so as to regulate the discharge pressure. A pressure monitoring gauge 28 is also connected in the pipe section 30 connecting the T-coupling 26 with the pressure switch device while a disconnect switch assembly 32 is electrically connected between the pressure switch device 22 and the underground cable 34 connected to the pump unit. Electrical connections are also established from the motor control box 20 to the pump unit through the electrical cable 36.

In accordance with the present invention, the drop pipe 14 extends into an elongated tubular 6 inch diameter casing 38 made of polyvinyl chloride (NSF) plastic material 40 within which one or more pressure compensator units 40 are housed through which water under pressure is conducted to the outlet conduit 24 connected to the upper end of the casing 38 by means of the elbow 42. The casing 38 may therefore extend above the ground line 44 by a suitable amount while the pressure compensator unit 40 may be located below the frost line so as to avoid any damage thereto because of extremely low temperatures. The electrical power cable 36 from the motor control box 20 extends through the casing 38 and the 4 inch polyvinyl chloride (NSF) plastic material extension 46 extending therebelow toward the pump unit.

Referring now to FIGURE 2, the casing 38 is closed at its upper end by a cap 48 through which a discharge conduit section 50 extends so as to center the casing 38 in concentric relation thereto and supply water under pressure through elbow 42 to the outlet conduit 24 above ground. At the lower end of the casing 38 a pipe reducer 52 connects the casing to the reduced diameter casing section 46 and supports a plastic, spacer washer 54 through which the drop pipe 14 extends into the casing 38 so as to be axially aligned with the conduit section 50. The electrical power cable 36 also extends through an opening in the spacer washer 54.

The conduit section 50 and drop pipe 14 are respectively connected by adapters 56 and 58 to internally threaded connector fittings 60 and 62 between which a perforated pipe section 64 is assembled forming part of the pressure compensator unit 40 aforementioned. The perforated pipe section will conduct water under pressure between the conduit sections 14 and 50 but will also establish fluid communication with an expandible cham-

ber 66 formed thereabout through a plurality of small, staggered holes 68 formed in the pipe section 64 for this purpose. In the illustrated embodiment, eight of such holes 68 are shown. The expansible chamber 66 is formed about the perforated pipe section by means of an elongated tubular member 70 made of a suitable, yieldably elastic material such as rubber.

Referring now to FIGURES 6 and 7 as well as FIGURE 2 will be observed that the tubular member 70 is clamped to the fittings 60 and 62 adjacent the opposite axial ends 72, by a pair of stainless steel clamping rings 74 so as to completely enclose the perforated pipe section 64 between the ends 72. Also mounted in fixed spaced relation to each other are a pair of end caps 76 and 78 which extend radially beyond the clamping rings 74, the end cap 76 being held assembled between the fitting 60 and the adapter 56 while the end cap 78 is assembled between the fitting 62 and the adapter 58. In the collapsed condition of the tubular member 70 shown in FIGURE 2, the ends 72 of the tubular member are axially spaced by a small amount from the end caps 76 and 78. However, when the tubular member is fully expanded as shown in FIGURE 3, the ends of the tubular member are displaced into engagement with the end caps so as to limit further axial expansion of the chamber 66 by the water under pressure and thereby effectively seal the chamber at the axial ends about the fittings 60 and 62. Radial expansion of the tubular member on the other hand is limited by the internal walls of the tubular casing 38.

With reference to FIGURE 9, it will be observed that pressure is maintained in the water supply system during use by energizing the pump unit through the drive motor 80 to operate the pump 82 maintaining a discharge pressure within a predetermined pressure range by means of the pressure switch device 22. For example, the motor 80 may be kept energized to drive the pump 82 as long as the discharge pressure sensed by the pressure switch device 22 is between a lower limit of 20 p.s.i. and an upper limit of 50 p.s.i. When the pressure exceeds 50 p.s.i., the pressure switch 22 is operative through the motor control 20 to deenergize the motor 80. After the motor is cut-off, the discharge pressure will decrease and when it decreases below the lower limit of 20 p.s.i. the pressure switch device 22 is operative through the motor control to reenergize the motor to start operation of the pump 82. In order to regulate the aforementioned increase and decrease in the pressure, and thereby meet any normal demand, one or more of the pressure compensator units 40 are mounted in the fluid supply line between the pump and the outlets. Accordingly, as the pressure within the fluid supply line approaches the upper limit of its operating pressure range, the tubular member 70 will be expanded to the condition shown in FIGURE 3. As long as the pumping system is in operation, the pressure compensating units 40 will expand and contract continually according to the pumping pressure as it ranges from 20 p.s.i. to 50 p.s.i. The pressure compensating units 40 expand under pressure from the pump until pressure reaches 50 p.s.i. when the pump automatically cuts off. The pressure compensating units 40 then begin contraction forcing water out through the outlet 18, until pressure drops to 20 p.s.i. at which time the pump will begin running and cycle is repeated. The continual expansion and contracting of the pressure compensating units 40 maintain pressure within the operating range of 20 p.s.i. to 50 p.s.i. regardless of the demand, this being accomplished without the need of any auxiliary water tanks connected to the water supply line.

As indicated hereinbefore, a plurality of units 40 may be mounted within the tubular casing 38 depending upon the requirements of the system. Further, although the units 40 are shown mounted in a vertical position, it will be appreciated that they may also be mounted in a horizontal position. FIGURE 8 accordingly shows such an installation wherein a pressure compensator unit gen-

erally referred to by reference numeral 40' is mounted horizontally within a horizontally positioned casing 38', the outlet conduit 24' being directly connected to the unit 40' by the elbows 84 and 86 and pipe section 88. 5 Conduit section 90 connects the unit to the pump while the power cable 36' supplies electrical energy to the motor operated pump from the motor control box 20. The arrangement shown in FIGURE 8 is therefore also 10 associated with the pressure switch device 22, pressure gauge 28 and disconnect switch 30 as described in connection with FIGURES 1 and 2 and operates in the same manner to regulate the supply of water under pressure from a deep well source.

The foregoing is considered as illustrative only of the 15 principles of the invention. Further, since numerous modifications and changes will readily occur to those skilled in the art, it is not desired to limit the invention to the exact construction and operation shown and described, and accordingly all suitable modifications and 20 equivalents may be resorted to, falling within the scope of the invention as claimed.

What is claimed as new is as follows:

1. In combination with a pump for supplying water from a well under a discharge pressure within a predetermined pressure range having an upper and lower limit, 25 a pressure compensating device comprising a conduit connected to said pump having at least one perforated portion below ground, a casing enclosing said perforated portion of the conduit and expansible chamber means mounted within said casing about the perforated portion 30 of the conduit for expansion to a volume limited by contact with the casing in response to pressure approaching said upper limit.

2. The combination of claim 1 wherein said expansible 35 chamber means comprises an elongated tubular member made of a yieldably elastic material, axially displaceable means clamping the tubular member to the discharge conduit at spaced locations beyond opposite axial ends of the perforated portion of the conduit, and sealing means 40 engageable with the tubular member in response to expansion thereof for limiting axial displacement of the clamping means to seal the perforated portion of the discharge conduit within the tubular member.

3. The combination of claim 2 wherein said sealing 45 means comprises end caps secured at axially fixed locations to the conduit extending radially beyond the clamping means.

4. The combination of claim 3 including means mounting the perforated portion of the conduit and the tubular member in concentric relation within the casing, said tubular member being collapsible about the perforated portion.

5. The combination of claim 1 including means mounting the perforated portion of the discharge conduit in concentric relation to the casing limiting contraction of the expansion means about the perforated portion.

6. The combination of claim 5 wherein said expansible 60 chamber means comprises an elongated tubular member made of a yieldably elastic material, axially displaceable means clamping the tubular member to the conduit at spaced locations beyond opposite axial ends of the perforated portion of the conduit, and sealing means engageable with the tubular member in response to expansion 65 thereof for limiting axial displacement of the clamping means to seal the perforated portion of the conduit with the tubular member.

7. A pressure compensating pumping system comprising 70 a motor operated pump, a conduit connected to said pump conducting fluid under discharge pressure of the pump, pressure operated switch means connected to the conduit for controlling operation of the pump to maintain the discharge pressure within a predetermined pressure range, and pressure compensator means operatively connected to said conduit regulating the discharge pressure 75 to meet demand comprising at least one perforated sec-

tion in said conduit, an expansible tubular member mounted in concentric relation about the perforated section having opposite axial ends, axially displaceable means clamping said ends of the tubular member to the conduit for sealing the perforated section within the tubular member and rigid casing means enclosing the tubular member for limiting axial and radial expansion thereof.

8. In combination with a pump connected to a conduit, a pressure compensator connected to said conduit for regulating the discharge pressure within a predetermined pressure range to meet demand, comprising at least one perforated section in said conduit, an expansible tubular member mounted in concentric radially spaced relation to the perforated section throughout the length thereof, axially displaceable means clamping opposite axial ends of the tubular member to the conduit for sealing the perforated section within the tubular member and rigid

10

15

casing means enclosing the tubular member and engageable therewith for limiting radial expansion of the tubular member.

9. The combination of claim 8 including sealing means fixedly secured to the conduit in enclosing relation to the axial ends of the tubular member and the clamping means for limiting axial expansion of the tubular member.
